Application January 13, 1939, Serial No. 250,770

25 Claims.

(Cl. 29—10)

This invention relates to machines for attaching decorative articles, such as gems or stones, and more particularly artificial stones such, for example, as rhinestones, to sheet material for the purpose of ornamentation or embroidery. It will be understood that the machine of the invention may also be employed for attaching other decorative material or articles capable of attachment in a similar manner to gems or stones, as, for instance, articles made of wood, plastics, metal, etc., which may be in various colors, shapes and styles.

The machine of the invention is an improvement over that described in U. S. Patent 1,994,250, granted March 12, 1935, to Frederick J. Meyers and Anton A. La Russa.

In general, our improved machine applies each rhinestone or other brilliant or other decorative article to the sheet material or fabric by means of a mounting punched from a sheet, preferably of metal, and formed with a back portion having prongs which are forced through the fabric from the reverse side. The stone is then automatically placed within the prongs and they are subsequently crimped or bent over the front surface or facets of the stone securing it tightly to the fabric.

It will be understood that in decorating dress fabrics, for example, with rhinestones applied in this manner, the stones are usually arranged in the form of some figure or design and that for a single gown it is necessary to apply a very large number of stones. In order to keep the cost of the gown within reason, it is necessary that these stones be quickly, neatly and uniformly mounted upon the fabric, and it is, of course, important that they be firmly secured so that they will remain in place during the ordinary wear of the garment.

The several advantages of the present invention will become apparent from a reading of the following specification, but briefly they include more rapid and reliable operation resulting from improvements in the mechanism for handling the individual stones to place them in proper position for the crimping operation, to improvements in selecting the individual stones from the supply heap, and also improvements in the mechanism for forming the mountings and for performing the crimping, the stones being secured firmly and tightly, regardless of the nature and thickness of the sheet material or fabric to which the stones are attached.

A preferred embodiment of this invention is illustrated in the drawings, but it is to be under-

stood that the disclosure in these drawings and in the following description is illustrative only, and that the scope of the invention is limited only by the appended claims.

5. Referring to the drawings:

Fig. 1 is a side elevational view of the machine taken partly in section along broken line 1—1 of Fig. 2;

Fig. 2 is a bottom view of the machine;

10 Fig. 3 is a sectional view taken along line 3—3 of Fig. 1;

Fig. 4 shows in detail the head portion of the machine illustrated generally in Fig. 1;

15 Fig. 5 is a sectional view taken along line 5—5 of Fig. 4;

Fig. 6 is a view looking into the empty stone hopper;

Fig. 7 is a sectional view of the foot portion taken along line 7—7 of Fig. 1;

20 Fig. 8 is a sectional view taken along line 8—8 of Fig. 10, showing cam mechanism of the foot portion;

Fig. 9 is a sectional view of the foot portion taken along line 9—9 of Fig. 8;

25 Fig. 10 is a sectional view taken along the broken lines 10—10 of Figs. 8 and 9;

Figs. 11, 12, 14 and 16 are sectional views of the foot portion showing four successive steps in the operation of fastening a stone to fabric, Fig. 14 showing the stone mounting in a section taken along the line 14—14 of Fig. 15;

30 Fig. 13 is a plan view of a fragment of the metal strip from which stone mountings are punched, showing one mounting partially severed from the strip;

Fig. 15 is a plan view of the metal strip of Fig. 13 with the stone in place on the fabric previous to the crimping operation;

35 Fig. 17 is a sectional view of the stone in position over the anvil previous to the locking operation;

Fig. 18 is a sectional view of the locking operation;

40 Fig. 19 is a plan view of our improved mounting;

Figs. 20 and 21 are front and rear views, respectively, of a fragment of fabric on which a stone has been mounted by the machine of our invention;

45 Fig. 22 is an enlarged sectional side view of a stone mounted on fabric;

Fig. 23 shows one form of stone-holding and crimping tool;

50 Fig. 24 shows an alternative form of stone-

holding and crimping tool incorporating an auxiliary hammer-blow mechanism;

Fig. 25 is a detailed sectional view of part of the hammer mechanism illustrated in Fig. 24 at the instant the hammer is released;

Fig. 26 is a development or layout of the surface of the cylindrical cam which controls the operation of the head portion of the machine.

Referring first to Fig. 1, the machine may, for convenience in describing it, be divided into a base portion shown at the lower left-hand corner of the figure, a head portion at the upper right-hand corner, and a foot portion at the lower right-hand corner. These three portions are secured to a horizontal U-shaped frame 1.

Referring now to Figs. 1 and 2, the machine is driven through a power source which is here illustrated as a pulley 2 driven by belt 3, operating a one-revolution clutch 5 through a reduction drive 4. This type of clutch, which is a well known device, drives the machine through one complete cycle at each operation of clutch control 6. It is usually convenient to couple this control with a floor pedal allowing the machine to be controlled by the operator's foot, leaving the hands free to manipulate the fabric upon which the stones are being mounted.

The output side of clutch 5 drives a rotating shaft 7 and on this shaft are mounted a cylindrical cam 8 and a radial cam or eccentric 9. The follower 10 of the cylindrical cam is connected through a pivoted driving link 11 to reciprocating rod 12 to which it imparts a reciprocating motion controlled by the shape of cam 8. At the end of rod 12 is a rack 13 which meshes with pinion 14 to drive the mechanism in the head portion of the machine.

The mechanism in the head portion includes a stone-carrying and crimping tool 15 comprising a shaft 16 mounted near one end to slide or reciprocate in a sleeve 17 pivoted to the frame at 18. Shaft 16 preferably should be formed with a keyway or at least one flat surface to prevent it from rotating about its own axis. The shaft in the illustrated example is of square cross-section. At the other end of shaft 16 is a stone-carrying tip 19 which also performs the function of a crimping tool later to be described.

The stone-carrying and crimping tool is actuated by a link 20 secured at one end to pinion 14 and bifurcated at the other end to span a roller 22 which is the follower of a face cam 23 secured to the frame 1. Pin 21 serves as an axle for roller 22. The axis of pinion 14 is at the center of part of the curve of cam 23. It will be seen that as pinion 14 revolves, the stone-carrying tip 16 follows a path of which the position shown in Fig. 1 is about mid-way.

Fastened to the head portion of frame 1 is a stone hopper 24 having an inclined bottom 25 and a false bottom 26 pivoted at the center. The side 27 of the hopper is, in the illustrated example, cylindrical. The false bottom 26 of the hopper, having a circular row of equally spaced holes 64 near its periphery, is slowly rotated in intermittent motion by means of a ratchet 28 and pawl 29 which are shown in Fig. 5. The pawl is moved by crank 30 coupled by a ball and socket joint 31 to connecting link 32. This connecting link is, in turn, pivoted to reciprocating rod 12 which actuates it. A flat brush 65 (Figs. 1, 4 and 6) is secured around part of the inside wall 27 of the hopper and arranged so that the ends of its bristles normally touch the surface of false bottom 26. This brush serves to retain the stones

in place in holes 64 while the false bottom rotates. A vacuum duct 33, part of which may be flexible, interconnects stone-carrying tip 19 and suction pump 34. The suction pump is actuated by cam or eccentric 9.

The foot portion of the machine is below the head portion and includes mechanism which cooperates with that included in the head. The mechanism in the foot portion is illustrated in various detail in Figs. 8-18, inclusive.

Referring first to Figs. 7-10, there is illustrated a cover-plate 35 screwed to frame 1. The upper surface of this cover-plate is smooth and suitably curved to allow the fabric to which the stones are being fastened to slide easily upon it. Beneath the center part of the cover-plate is a punch 37 which reciprocates vertically through an aperture in the complementary die 36. Secured to the top surface of the die and to one side of the aperture therethrough is an anvil 38, the function of which will be described later. Punch 37 is reciprocated vertically through the die by a face cam 39, which when rotated by shaft 7, coacts with roller 40 on the post 43 which supports punch 37. Post 43, which is of circular cross-section, slides vertically within the cylindrical bore of a square column 44. This column supports on its upper end die 36 and fits into a bed-piece 45 to which rollers 42 are pinned. Bed-piece 45 is supported in casing 46 which is secured to frame 1. Between one side of bed-piece 45 and square column 44 is a filler block 68 (Fig. 9) of a thickness slightly greater than the length of roller 40. This filler block may be withdrawn by means of a notch cut near the top thereof, allowing the square column to move back releasing roller 40 from the groove of cam 39 and thereby permitting the removal of post 43 together with punch 37. Die 36, anvil 38, and punch 37 are arranged to be reciprocated horizontally as a unit, in casing 46, by the rotation of cam 41 which coacts with rollers 42. The exterior surface of cam 41 is in effect the periphery of face cam 39. The horizontal distance over which the die and punch are reciprocated is represented at D in Fig. 10 as the distance between the centers of the die 36 and anvil 38.

Referring to Fig. 7, there is shown a guide-piece 69 secured to frame 1, the upper surface of the guide-piece conforming to the surface of the cover-plate. Through guide-piece 69 a slot extends approximately parallel with the upper surface, and a corresponding slot extends horizontally through die 36 and communicates with a suitable space on the opposite side of the die beneath the cover-plate and thence beneath and away from the frame. Through this slot and space a strip or ribbon 48, preferably of metal, is caused to travel in a direction from left to right, as Fig. 7 is viewed, by virtue of the reciprocation of the die above mentioned. It is understood that the ribbon is fed from a spool or reel (not shown) suitably supported in or near the machine. From this ribbon are punched the mountings 49 (Figs. 13 and 19-21) by which the stones are secured to the fabric. Ribbon 48 is constrained by clutch 50 to move through slot 47, as Fig. 7 is viewed, only in the direction indicated by the arrows.

The operation of our machine is as follows: Starting at the position shown in Fig. 1, the stone-carrying and crimping tool 15 first swings toward hopper 24 into which stone-carrying tip 19 enters at a position where a single stone is delivered right side up (see Fig. 4). By means

of suitable suction through vacuum duct 33 the stone is held in tip 19 while tool 15 swings back to a position in alignment with die 36.

Meanwhile, punch 37 passes upwardly through die 36 punching out of ribbon 48 a metal mounting 49, as shown successively in Figs. 11 and 12. At this stage stone-holding tip 19 approaches the moving punch vertically, as shown in Fig. 12. Punch 37 continues its upward movement forcing the prongs 53 of the mounting 49 through fabric 51 from the reverse side, as shown in Fig. 14. As stone-holding tip 19 and punch 37 continue to approach each other somewhat closer, as shown in Fig. 16, the tips of the prongs 53 are bent slightly over the surface or facets of the stone at the girdle by reason of the shape and angle of the inner surface of tip 19. The slots, or guideways 19a (Fig. 17) in the crimping surface of tip 19, which though preferred are not absolutely necessary, serve to guide the tips of the prongs in the direction of the center of the table of the stone, so that when the final crimping, or locking, operation is completed, as about to be described, the prongs of the setting will be straight and true. As a result of this preliminary crimping or setting operation, the tips of prongs 53 are bent inward sufficiently to cause the stone, setting and fabric to be held compactly together and also to prevent the stripping of the setting from the fabric upon the removal of the support from beneath the setting by the withdrawal of punch 37.

The preliminary crimping is accomplished by the partial descent of crimping tool 15 carrying the tip 19 which is controlled by the shape of cam 8 (Figs. 1, 2 and 26). As will be described later, this cam is so shaped that the crimping tool descends further during the final crimping, or locking, operation than it does during the preliminary crimping operation.

The final crimping, or locking, operation contemplated by our invention to complete the attachment of the stone and mounting to the fabric is as follows: After the completion of the preliminary crimping operation illustrated in Fig. 16, crimping tool 15, including tip 19, is reciprocated upwardly a short distance, as indicated in Fig. 17, and punch 37 is reciprocated downwardly below the top of the die. Then the unit comprising die 36, punch 37 and anvil 38 is reciprocated horizontally in the direction of the horizontal arrow in Fig. 17, bringing anvil 38 into alignment with tip 19 of the crimping tool. The crimping tool then again descends, forcing mounting 49 against the upper surface of anvil 38 and crimping the prongs 53 of the mounting firmly against the stone, as shown in Fig. 18.

During both the preliminary crimping operation and the final crimping, or locking, operation, the pressure of tip 19 against prongs 53 and the stone is limited and cushioned to a predetermined extent by the inclusion of a cushioning spring 54 within the shaft of the crimping tool 15, as shown in Fig. 23. The construction is believed to be plain from the drawings, in which it is seen that spring 54 is compressed as the plunger 55 slides inside the hollow end of tool 15.

Crimping tip 19, which preferably screws onto the end of the plunger 55 for ready replacement, contains a bore communicating with the conical inner surface of the tip, which forms a seat for the stone, and with a central bore in plunger 55 which, in turn, communicates with vacuum duct 33, so that the required stone-holding suction may be applied at tip 19.

The preliminary crimping operation may be sufficient to effect a firm fastening of the stone in the mounting, especially if the fabric to which the stone is secured is of thin and soft material.

However, if the fabric is thick or resilient, or if the metal of which the mountings are made is stiff, the two step crimping operation, which includes the locking operation above described immediately following the preliminary crimping operation, results in securely mounting the stone upon the fabric.

Under some conditions, a modified form of crimping tool may be employed, as shown in Fig. 24. This crimping tool is similar to that illustrated in Fig. 23, but includes the added feature of a spring hammer which, for example, may utilize the principle employed in the well-known automatic center punch. To this end, the upper portion 16 of the shaft of the tool is bored out to receive a hammer spring 56 which is adjustably retained by a screw plug 57. Below spring 56 is a hammer 58. Secured to plunger 55 is a stem 59 having a shoulder 60 near the upper end thereof. Between this shoulder and the face of hammer 58 is a releasing pin 61, normally pressed to one side by leaf spring 62 (see also Fig. 25) in a locked position.

When tip 19 is pressed upwardly plunger 55 slides within the tool 15 compressing spring 54, as previously described in connection with Fig. 23, and simultaneously compresses spring 56 by virtue of the pressure of shoulder 60 against pin 61 which in turn presses upwardly on the face of hammer 58. When plunger 55 is moved upwardly a sufficient distance the rounded end of pin 61 will have reached position 63 where the diameter of the bore decreases. The pressure of the inside of the bore against the end of pin 61 will then move the pin horizontally against leaf spring 62 releasing shoulder 60 and allowing hammer 58 to fall under the pressure of the compressed spring 56. The hammer then strikes a blow against the end of stem 59 which blow is transmitted to tip 19 of the crimping tool then in contact with the prongs of the mounting supported, in turn, on the anvil 38. A sharp blow of this nature results in a very tight fastening of the stone to the fabric.

Fig. 25 is an enlarged drawing of a part of the spring-hammer mechanism shown in Fig. 24 and illustrates the positions occupied by the several parts at the instant the hammer is released and before it has delivered its blow to the end of stem 59.

The operation of the stone hopper is as follows:

Referring to Figs. 1, 4, 5 and 6, as rod 12 reciprocates, its motion is transmitted through ball-and-socket joint 31 to crank 30, rotating ratchet 28 through the medium of pawl 29 (Fig. 5). The ratchet and pawl are mounted above bottom 25 of the hopper and beneath the false bottom 26. Link 32, lever 30 and the teeth of ratchet 28 are so designed and adjusted that a complete excursion of reciprocating rod 12 rotates false bottom 26 an angular distance equal to that between the centers of holes 64 and 64a, as shown in Fig. 6. As the disc rotates in the direction of the arrow shown in Fig. 6, some of the individual stones in the pile or mass 66 (Fig. 4) are tumbled about and by gravity a stone will fall right-side up in each of holes 64. These holes are of such size and shape that the stone will be retained only if it is right-side up. Consequently, if the size or shape of the stones to be

attached is materially changed another disc should be substituted having holes proportioned to the changed size of the stone. (This is also true, of course, of tip 19 of the carrying and crimping tool 15 and of the punch 37 and die 36, all of which are removable for ready replacement.) As disc 26 rotates in a clockwise direction (looking into the top of the hopper), the holes in which the stones are conveyed are moved upwardly above the surface of the mass until they come beneath retaining means 65, which, for example, may comprise a flat brush secured around the side of the hopper so that the free ends of its bristles press lightly against the stones in place in the holes. To accomplish this the bristles must usually be long enough to brush against the face of the disc. The brush 65 is also useful to remove from a hole any stone which by accident has been retained wrong side up. As a given stone continues to move around on the periphery of the disc it approaches position 67 of Fig. 6 which is the point at which stone-carrying tip 19 of tool 15 descends to pick up a stone. It will be observed that at position 67 the side 27 of the hopper has been cut out to form a recess allowing tip 19 to pass into the hopper and seize a stone.

Fig. 26 is a layout or development of the cylindrical cam 8 shown in Figs. 1 and 2. Point Z represents approximately the position shown in Fig. 2 of the follower 10 in the cam. The exact shape of this cam, and the shapes of the other cams above described, can readily be predetermined by one skilled in the art, in view of the required operations hereinabove explained. It may be noted, however, that the positions indicated by the arrows at X and at Y in Fig. 26 are respectively the positions of the follower to effect the crimping operation and the locking operation. In the drawing, the distance between the arrowheads at Y and the arrowheads at X appear to be almost the same, but actually the cam is cut so that during the locking operation the tip of the crimping tool descends further than it does for the preliminary crimping operation.

As mentioned at the beginning of this specification, the machine of our invention may be employed for attaching decorative articles other than gems, or stones, and the term "stones" as used in the appended claims is therefore intended to include other decorative articles capable of attachment in a similar manner to gems, or stones.

It will be understood that the above constitutes an exemplifying disclosure of our improvements in stone setting machines, and that changes may be made without departing from the spirit of the invention, the scope of which is set forth in the appended claims.

We claim:

1. In a machine for attaching ornamental stones to sheet material, the combination of a die, a punch coacting with said die to form a stone mounting and to push said mounting through said die to the surface thereof, and a stone-holder having a tip conforming to the surface of the stone with which it comes in contact, said tip comprising a crimping tool, said tool being movable to and from said surface of the die and coacting with said punch and die to force portions of said mounting through said material and crimp them over a stone.

2. In a machine for attaching ornamental stones to sheet material, the combination of a

die, a punch arranged to reciprocate upwardly through said die and adapted to cut and form from sheet metal a stone mounting having prong portions and to carry said mounting upon the punch to the upper surface of the die, a crimping tool mounted for downward approach to said die, means including said crimping tool to pick up and deposit a stone, means causing the approach of said punch and said crimping tool in coaction with said die to set a stone in said mounting, and means forcing said crimping tool against said mounting to crimp the prong portions thereof over the surface of said stone.

3. In a machine for attaching ornamental stones to sheet material, the combination of a die, a punch arranged to reciprocate vertically through said die and adapted to cut and form from sheet metal a stone mounting having prong portions and to carry said mounting upon the punch to the upper surface of the die, a crimping tool mounted for vertical approach to said die, suction means including said crimping tool to pick up and deposit a stone, means causing the approach of said punch and said crimping tool in coaction with said die to set a stone in said mounting, and means forcing said crimping tool against said mounting to crimp the prong portions thereof over the surface of said stone.

4. In a machine for attaching ornamental stones to sheet material, a stone-carrying tool having a tip shaped to fit a stone and mounted for downward approach to said sheet material, means for retaining a stone in said tip, means causing the prongs of a mounting to pierce said sheet material from the reverse side and force said tip and stone into coaction with said mounting, and means combined with said tip to crimp said prongs against the surface of said stone.

5. In a machine for attaching ornamental stones to sheet material, a stone-carrying tool provided with a tip adapted to fit a stone, said tip having guideways shaped to guide and crimp the prongs of a mounting over the surface of said stone.

6. In a machine for attaching ornamental stones to sheet material, the combination of means for supporting a stone mounting in attachable relation to the sheet material, a crimping tool, mechanically actuated means for causing the crimping tool to approach the mounting support to force the prongs of the mounting through the sheet material and crimp them upon a stone, means associated with the crimping tool for picking up and carrying a stone, and means for moving the tool out of the line of approach to the mounting support to cause the tool to pick up a stone prior to its coaction with the mounting support.

7. In a machine for attaching ornamental stones to sheet material, the combination of a punch and die mechanism for forming a stone mounting and supporting the same in attachable relation to the sheet material, a crimping tool, mechanically actuated means for causing the crimping tool to approach the punch and die mechanism while the mounting is held therein to force the prongs of the mounting through the sheet material and crimp them upon a stone, and means for moving the crimping tool out of the line of approach to the mounting to pick up a stone prior to the coaction of the tool with the punch and die mechanism.

8. In a machine for attaching ornamental stones to sheet material, the combination of means for supporting a stone mounting in attach-

able relation to the sheet material, a crimping tool, means for reciprocating the crimping tool into coaction with the mounting support to force the prongs of the mounting through the sheet material and crimp them upon a stone, means associated with the crimping tool for picking up and carrying a stone, and means for swinging the crimping tool out of its line of reciprocation to pick up a stone prior to its approach to the mounting support.

9. In a machine for attaching ornamental stones to sheet material, the combination of means for supporting a stone mounting in attachable relation to the sheet material, a crimping tool, mechanically actuated means for causing the crimping tool to approach the mounting support to force the prongs of the mounting through the sheet material and crimp them upon a stone, means associated with the crimping tool for picking up and carrying a stone, a stone-selecting mechanism for removing individual stones from a mass thereof, and means for moving the crimping tool into coaction with said stone-selecting mechanism to pick up a stone therefrom prior to the approach of the crimping tool to the mounting support.

10. In a machine for attaching ornamental stones to sheet material, the combination of a support for the sheet material, a movable support for a stone mounting arranged to reciprocate with respect to the material support, a crimping tool arranged to reciprocate with respect to the material support, means associated with the crimping tool for causing the same to pick up and carry a stone, means for actuating the tool to pick up a stone, and means for bringing said mounting support and crimping tool into coaction in cooperation with the material support to force the prongs of the stone mounting through the material and crimp them upon the stone.

11. In a machine for attaching ornamental stones to sheet material, the combination of a die, a punch arranged to reciprocate upwardly through said die and adapted to cut and form from sheet metal a stone mounting having prong portions and to carry said mounting upon the punch to the upper surface of the die, a crimping tool mounted for downward approach to said die, means including said crimping tool to pick up and deposit a stone, means causing the approach of said punch and said crimping tool in coaction with said die to place a stone in said mounting and forcing said crimping tool against said mounting to crimp the prong portions thereof over the surface of said stone, an anvil adjacent said die, means moving said die, punch and anvil as a unit horizontally beneath said sheet material to align said crimping tool and said anvil with the mounted stone therebetween, and hammer mechanism causing said crimping tool to strike a blow on said mounting against said anvil.

12. In a machine for attaching ornamental stones to sheet material, the combination of a die, a punch arranged to reciprocate upwardly through said die and adapted to cut and form from sheet metal a stone mounting having prong portions and to carry said mounting upon the punch to the upper surface of the die, a crimping tool mounted for downward approach to said die, means including said crimping tool to pick up and deposit a stone, means causing the approach of said punch and said crimping tool in coaction with said die to place a stone in said mounting and force said crimping tool against

said mounting to crimp the prong portions thereof over the surface of said stone, an anvil adjacent said die, means aligning said anvil and crimping tool with the mounted stone therebetween, and hammer mechanism causing said crimping tool to strike a blow on said mounting against said anvil, whereby said stone is locked in said mounting.

13. In a machine for attaching ornamental stones to sheet material, the combination of a die, a punch arranged to reciprocate upwardly through said die and adapted to cut and form from sheet metal a stone mounting having prong portions and to carry said mounting upon the punch to the upper surface of the die, a crimping tool mounted for downward approach to said die, means including said crimping tool to pick up and deposit a stone, means causing the approach of said punch and said crimping tool in coaction with said die to place a stone in said mounting and force said crimping tool against said mounting to bend the prong portions thereof over the surface of said stone, an anvil adjacent said die, means aligning said anvil and crimping tool with the mounted stone therebetween, and means causing said crimping tool to force said mounting against said anvil, whereby said stone is locked in said mounting.

14. In a machine for attaching ornamental stones to sheet material, a crimping tool, and hammer-blow mechanism combined with said crimping tool.

15. In a machine for attaching ornamental stones to sheet material, the combination of a die and punch mechanism for forming a stone mounting, means including said mechanism for supporting the mounting in attachable relation to the sheet material, a crimping tool, mechanically actuated means for causing the crimping tool to approach the supporting means while the mounting is held therein to force the prongs of the mounting through the sheet material and effect a preliminary crimping of the prongs upon a stone, said die and punch mechanism including an anvil, means for shifting said mechanism to align the anvil and crimping tool, and means for causing the crimping tool and anvil to effect a final crimping of the mounting.

16. In a machine for attaching ornamental stones to sheet material, the combination of a die and punch mechanism for forming a stone mounting from sheet metal, means including said mechanism for supporting the mounting in attachable relation to the sheet material, a stone-carrying crimping tool, mechanically actuated means for causing the crimping tool to approach the supporting means while the mounting is held therein to force the prongs of the mounting through the sheet material and effect a preliminary crimping of the prongs upon a stone carried thereby, said die and punch mechanism including an anvil, means for shifting said mechanism to align the anvil and crimping tool, and means for causing the crimping tool and anvil to effect a final crimping of the mounting.

17. In a machine for attaching ornamental stones to sheet material, the combination of a die, a punch arranged to reciprocate vertically through said die to cut and form from sheet metal a stone mounting having prong portions and to carry said mounting upon the punch to the upper surface of the die, a crimping tool, mechanically actuated means for causing the crimping tool to approach the punch and die mechanism while the mounting is supported upon the

punch to force the prongs thereof through the sheet material and effect a preliminary crimping of the prongs over a stone, said punch and die mechanism including an anvil, means for shifting said mechanism laterally to bring the anvil beneath the crimping tool, and means for causing the crimping tool and anvil to effect a final crimping of the mounting.

18. In a device for selecting and delivering ornamental stones or similar articles, a hopper having a delivery point and an inclined bottom and adapted to hold in its lower portion a mass of stones, said bottom comprising a rotatable disc having a circular row of equally spaced stone-carrying holes near its periphery, driving means rotating said disc intermittently a distance equal to the spacing between the centers of adjacent holes, and means attached to said hopper and extending over said row of holes for retaining the stones in said holes as said disc rotates conveying said stones to said delivery point.

19. In a machine for attaching ornamental stones or similar articles to sheet material, a hopper having an inclined bottom and adapted to hold a mass of stones in its lower portion bounded by a wall and said bottom, said bottom comprising a rotatable disc having a circular row of equally spaced stone-carrying holes near its periphery, driving means rotating said disc intermittently a distance equal to the spacing between the centers of adjacent holes, retaining means attached to said hopper and extending over said row of holes for retaining the stones in said holes as said disc rotates conveying said stones to a delivery position above the surface of said mass of stones, and a stone holder movable in timed relation to said disc to carry a stone from said delivery position to its place of attachment to said material.

20. In a machine for attaching ornamental stones to sheet material, the combination of a die, a punch arranged to reciprocate upwardly through said die and adapted to cut and form from sheet metal a stone mounting having prong portions and to carry said mounting upon the punch to the upper surface of the die, a crimping tool mounted for downward approach to said die, means including said crimping tool to pick up and deposit a stone, and means causing the approach of said punch and said crimping tool in coaction with said die to set a stone in said mounting.

21. In a machine for attaching ornamental stones to sheet material, the combination of a die, a punch arranged to reciprocate upwardly through said die and adapted to cut and form from sheet metal a stone mounting having prong

portions and to carry said mounting upon the punch to the upper surface of the die, a crimping tool mounted for downward approach to said die, suction means including said crimping tool to pick up and deposit a stone, means for causing the approach of said punch and said crimping tool in coaction with said die to set a stone in said mounting, and means forcing said crimping tool against said mounting to crimp the prong portions thereof over the surface of said stone.

22. In a device for selecting and delivering ornamental stones or similar articles, a hopper having a delivery point and an inclined bottom and adapted to hold in its lower portion a mass of stones, said bottom comprising a rotatable disc having a circular row of stone-carrying holes near its periphery, driving means rotating said disc, and means within said hopper and extending over said row of holes for retaining the stones in said holes as said disc rotates conveying said stones to said delivery point.

23. A combination according to claim 22 in which said retaining means comprises a brush extending along a portion of the inside wall of said hopper with the free ends of its bristles touching said rotatable disc and stones conveyed in the holes therein.

24. In a machine for attaching ornamental stones to sheet material, the combination of mechanism for forming from sheet metal a stone mounting having prong portions and supporting the same with the prong portions in position to pierce the sheet material, a crimping tool mounted to approach said prong portions, means including said crimping tool to carry and apply a stone to said sheet material opposite said prong portions, and means causing the approach of said crimping tool toward the mounting so as to cause the prong portions to pierce the sheet material around the stone and to bend them over the surface thereof.

25. In a machine for attaching ornamental stones to sheet material, the combination of means for supporting a stone mounting with the prong portions thereof in position to pierce the sheet material, a crimping tool mounted to approach said prong portions, means including said crimping tool to carry and apply a stone to said sheet material opposite said prong portions, and means causing the approach of said crimping tool toward the mounting so as to cause the prong portions to pierce the sheet material around the stone and to bend them over the surface thereof.
